(57) **CLAIM**

The ornamental design for a jar with a transparent windowed lid, as shown and described.

DESCRIPTION

FIG. 1 is a perspective view of a jar with a transparent windowed lid showing my new design;

FIG. 2 is front view thereof;

FIG. 3 is a back view thereof;

FIG. 4 is a right side view thereof;

FIG. 5 is a left side view thereof;

FIG. 6 is a top view thereof; and,

FIG. 7 is an exploded view thereof.

The details visible through the transparent portion of the lid in FIGS. 1 & 7 are not included in the claimed design and have been omitted for ease of understanding.

1 Claim, 5 Drawing Sheets
